UNITED STATES PATENT OFFICE.

CHARLES J. APPLETON, OF NEW YORK, N. Y., ASSIGNOR OF TWO-THIRDS
TO HUGO S. MACK AND ELBERT A. WHITTELEY, OF SAME PLACE.

CIRCULAR-KNITTING MACHINE.

SPECIFICATION forming part of Letters Patent No. 510,829, dated December 12, 1893.

Application filed August 8, 1890. Serial No. 361,425. (No model.)

To all whom it may concern:

Be it known that I, CHARLES JAMES APPLETON, a citizen of the United States, residing in the city of New York, in the county and State 5 of New York, have invented certain new and useful Improvements in Circular-Knitting Machines, of which the following is a specification.

This invention relates to knitting machines 10 of the circular type, and has for its object to produce, in a machine of that class, a turned or overlapped welt or hem, such as has only been heretofore made on flat or straight machines. To this end I employ devices for putting out 15 of action the horizontal needles and for holding down the loops on the vertical needles in the proper position, said devices including hold-downs for holding the loops down and back of the vertical needles so as to allow 20 them to slide through the loops thereon and be ready to take the yarn for another course.

For full comprehension of my improvements, reference must be had to the accompanying drawings, and to the following detailed description wherein similar letters of 25 reference indicate like parts.

In said drawings, Figure 1 is a plan of a knitting machine embodying my invention. Fig. 2 is a transverse vertical section. Fig. 3 is a horizontal section taken through the operating cam on line X, X, Fig. 2, only a few of the horizontal needles being shown. Fig. 4 shows a detail of the cam for moving the hold-downs. Fig. 5 shows a detail of the 35 sprocket wheel and chain, and Fig. 6 shows a detail of the ratchet, pawl and tripping mechanism.

a, represents the circular plate carrying the horizontal needles a', which are arranged 40 radially thereupon in the usual manner.

b, is the stationary cylinder upon the outer face of which the vertical needles b', are situated,—their shanks or butts projecting into a cam groove d', in the cam cylinder d, which 45 operates said needles.

c, is the cam cap. c' is the drawing in cam for operating the horizontal needles a', the cam cap being fixed upon a central shaft g, so as to revolve therewith.

50 e, is the annular ring surrounding and fixed to the needle cylinder b,—a series of radial

grooves e², being formed in said ring to receive the lower arms of my hold-downs e' the same being pivoted therein in any suitable manner. The upper arms or ends of these 55 hold-downs are so configurated as shown, as to hold the stitches or loops down upon the vertical needles b'.

f, is a suitable yarn guide located contiguous to the needle cylinder. 60

g', is a toothed sector mounted loosely on a collar of the cam cap c, and intermeshing with a sector h, in the same plane, which latter is carried upon the upper end of a spindle k, journaled in an extension i', of the yoke i, 65 which is fastened to the cam cylinder d. The sector h, is slotted at h' to permit the passage of the yoke and said yoke is also fixed upon the upper portion of the central shaft g. This shaft passes centrally through the circular 70 plate a, and has a collar on its lower end, the yoke i, revolving therewith and with the cam cylinder,—the plate a being provided with downwardly projecting arms v, v, which abut against lugs v', v', formed on the bed plates z, 75 thus holding the plate and horizontal needles stationary.

Fixed upon the lower end of the spindle k is the disk j which has a tripping device j' on its under side arranged to move the disk in 80 either direction by the action of the pin r and pattern chain m' having cam links m², thereby throwing the horizontal needles in and out of action.

l is the main driving shaft, journaled underneath the bed plate z, and carrying a pinion l', which meshes with a gear l², formed upon the lower side of the cam cylinder d,—these gears being preferably set so that there will be two revolutions of the pinion to one of the 90 cylinder. Mounted loosely on the shaft l, contiguous to said pinion, is a sprocket wheel m, around which passes a pattern chain m', constructed so as to regulate the number of plain courses in the welt or hem, and length of the 95 fabric to be knit. At the side of the sprocket wheel, and preferably fixed upon the same sleeve, is a ratchet wheel n, with which engages a pawl n', carried upon the lower end of a spring actuated pin o, projecting through 100 the bed plate z. A disk p, is also fixed upon the driving shaft l, and has a projecting pin

p', so placed upon its face that the rotation of the shaft brings said pin over and above the point of a tripping plate *q*, pivoted on the pawl arm, so as to depress the pawl and move 5 the ratchet wheel one tooth. When the pin *p'* has passed the center of the tripping plate *q* it will then be passing over the large end of the plate depressing it, when the spring *o'* will raise the pawl arm and turn up the point of 10 the tripping plate so as to allow the pin *p'* to pass on the next revolution of plate *p* underneath the point of the plate and return it to its former position by coming in contact with the under side of the large end of the same, 15 thus throwing down the point of the tripping plate and resetting it in its normal position ready to operate the ratchet wheel at the next revolution.

r, is a spindle journaled vertically in the 20 bed plate *z*, having a spring *r'*, and an enlarged butt or end adapted to be impinged upon by cams or enlargements *m*², formed upon some of the links of the pattern chain *m'*, their number being proportionate to the 25 number of plain courses required in the welt or hem. As the driving shaft, sprocket wheel and chain revolve, the spindle *r* is raised each time its lower end encounters one of the cam links *m*² into position for its upper end to engage with the tripping device *j'*, and thus, 30 through the spindle or shaft *k*, to operate the sectors *h* and *g'*. A pin *g*² passes up from the cam piece *c*, to a curved slot *g*³, in the sector *g'*, and down to engagement with a swinging 35 cam piece *s*, pivoted to said cam piece *c*, on its under side. This serves to throw the horizontal needles out of operation while the vertical needles proceed with plain work.

t, is a roller journaled in the yoke *i*, in such 40 a position as to bear upon the lower arms of the hold-downs *e'*, as they pass and thus free their upper ends from the fabric, and at a point within said yoke directly opposite said roller, I fix a cam plate *u*, for raising the hold-downs into contact with the loops after the 45 vertical needles have descended and shut off the old loops and before they rise again. The hold-downs are so arranged that there are two hold-downs between each vertical needle and its adjoining vertical needle, so as to allow 50 the horizontal needles to pass centrally between the vertical needles and have on each side of each of them a hold down, thus leaving, when the vertical needles are knitting 55 plain work and the ribbing needles are thrown out of action, two hold downs between each two vertical needles as above described.

I may further describe the operation of my 60 machine as follows: Work being on the needles, and motion being given to the cam ring *d*, by the pinion *l'*, on shaft *l*,—and the other working parts being in position for making ordinary rib-work, one of the cams *m*², on the chain *m'*, engages the butt end of the spindle *r*, and raises it high enough for its upper end to engage the tripping device *j'*, and thus, (through spindle *k*) by moving sectors

h and *g'*, by pin *g*², working in groove *g*³, in sector *g'*, and moving cam *s*, throws the horizontal needles *a'*, out of operation while still 70 leaving the loops thereon. The vertical needles still continue knitting loops and courses, in the shape of a bag, tuck or pouch continually gaining in length (out of which the overlapped or turned welt is formed) until by the 75 assistance of the hold-downs a sufficient length is produced for the purpose required. Then another cam on the chain will cause the spindle *r* to engage with the tripping device *j'* which is pivoted on the under side of the disk. 80 The movement of the tripping device is limited by the pins *j*² on the disk *j* so that when the tripping device *j'* comes in contact with one of the pins it will move or turn the disk *j* in that direction returning the sectors to 85 their former position and bringing both sets of needles into operation, again forming ribbed work and completing the turned welt. Motion is given to the chain and its sprocket by the ratchet *n*, its pawl and tripping device *q*, 90 and the chain moves only one link during each revolution of the machine,—thus saving length of chain.

It will be readily seen from the foregoing, and from the drawings, that the essential features of my hold-down devices may be applied to circular rib knitting machines of any of the well known classes, the hold-downs being between the vertical needles and arranged in a manner to allow the horizontal 100 needles and the vertical needles to work at the same time, producing ribbed work, and also to work with the vertical needles when the ribbing needles are thrown out of operation for producing plain work on the said 105 needles. The hold-downs will then keep control of the loops until enough plain work is knit, the only necessary addition being means substantially such as I have shown for successively throwing said hold-downs into and out 110 of engagement with the needles and the loops carried thereby.

Having thus described my invention, I claim—

1. In a circular rib knitting machine the 115 combination with the vertical and horizontal needles and means for operating them of hold-downs *e'*, depressing roller *t*, lifting cam plate *u*, and ring *e*, said devices for holding down the loops arranged in such manner that two 120 of such hold-down devices will lie within each pair of vertical needles and one horizontal needle within each pair of hold-down devices, substantially as and for the purposes set forth.

2. In a circular rib knitting machine, the 125 combination of vertical and horizontal needles, means for operating the same, and means for throwing said horizontal needles automatically into and out of operation, with hold-downs adapted to hold the work down on the vertical needles when the horizontal needles are out of operation, and means for operating said hold-downs, substantially as described.

3. The combination with the cam-cap *a*, the drawing-in cam *c'*, the movable cam *s* provided with the pin *g²* for operating the horizontal needles of the sectors *g'* and *h*, spindle *k*, provided with tripping device *j'*, and spring actuated spindle *r*,—of the sprocket wheel *m*, and its pattern chain,—driving shaft *l*, ratchet *n*, pawl *n'*, tripping device *q*, and disk *p*, having pin *p'*, all being constructed and arranged substantially as and for the purposes set forth. 10
CHARLES J. APPLETON.
